KITE BALLOON

Domina C. Jalbert, Belmont, Mass., assignor to
Dewey and Almy Chemical Company, North
Cambridge, Mass., a corporation of Massachu-
sets

Application August 31, 1945, Serial No. 613,887

4 Claims. (Cl. 244—33)

This invention relates to kite balloons. Although, as will be apparent, the balloon may be adapted for many uses and can be made in numerous sizes, it is particularly designed for use where conservation of weight in the balloon structure is of paramount importance. Weight conservation is an absolute necessity in sea-rescue balloons, since the hydrogen capacity of any generator that may be a part of an aviator's "ditching kit" is strictly limited. The largest practical size of the sea-rescue gas generator is 40 cubic feet of hydrogen. Considering the gross lifting capacity of hydrogen as 32 grams per cubic foot, the "static" or hydrogen-created lift is but 1280 grams. Therefore, for the balloon to rise at all the weight of the flying line and all of the balloon structure cannot exceed 1280 grams and should not exceed more than 65% of the figure because residual or "free lift" of the balloon is required for effective service. Since the instant invention successfully meets the weight requirements of sea-rescue balloons, that model will be described as the preferred example.

One of the most important requirements in sea-rescue balloons is that they shall fly independently of weather conditions for a long time, for it frequently happens that the occupant of a life raft is not found for several days. Kite balloons utilize the lifting power of a lighter-than-air gas to lift the whole structure. Lighter-than-air lift is conveniently called "static lift." The lifting-fins, however, when the balloon is anchored cause it to act like a kite, and the lifting or kite effect, which conveniently is called the "dynamic lift," of even light winds is greater than the static lift due to the gas. The pressure of the wind on the balloon envelope not equipped with lifting-fins and anchored (i. e., flying captive) forces it progressively down toward the sea as the wind rises. A forty cubic foot spherical balloon is blown down to the sea in winds of about 35 to 45 miles an hour. But when the balloons are equipped with lifting-fins, the blow-down effect of wind pressure is counteracted by wind lift, or kite effect, and the balloons may ride even higher in stiff winds than in a light breeze.

The most common kite balloon, the barrage balloon, conserves its hydrogen supply and maintains its shape while flying by means of a balloonette, a gas-proof diaphragm, which is attached to the lower interior walls of the balloon in such a manner that air may be scooped into the balloonette, which swells up inside the balloon envelope and compresses the hydrogen gas

in the balloon above the diaphragm. When the temperature rises or the external pressure falls and the hydrogen gas expands, the balloonette is pushed downwardly by the hydrogen and some air is expelled. In this manner, fixed volumes of hydrogen are used to lift the balloon, yet the danger that a fixed volume of hydrogen will build up such a pressure that the balloon envelope will be ruptured is eliminated.

10 The weight limitations imposed on sea-rescue balloons make it impossible to use this effective device. A further difficulty has been that when a barrage balloon has been reduced in dimensions to 40 cubic feet capacity its stability practically vanishes; it lunges wildly in the air in all but the very lightest of winds, making it unsuitable for an antenna support.

My present kite balloon avoids these difficulties. It will fly without lunging or yaw, it will 20 rise in dead calms and fly in any wind up to a violent blow; it is not forced down by the wind like a balloon, but will climb into the wind like a kite and consistently will maintain a high angle to the horizontal, independent of the wind. It 25 may be packed in a package of approximately 125 cubic inches, and its total weight is below 750 grams. It will support a metallic antenna 400 or 500 feet long weighing 300 grams for sending and receiving signals on the international 30 distress wave length and, even when so loaded, will exert a net free lift of more than 250 grams. This is sufficient to launch the balloon straight up between trees, a very valuable feature in jungle or tropic rescue work.

35 The invention will be apparent from the specification and from the drawing in which:

Figure 1 is a perspective view of the balloon in flight,

Figure 2 is a top view of the balloon, and

40 Figure 3 is a section through the balloon on the line 3—3 of Figure 2.

In carrying out my invention, I provide a balloon envelope 10 which is approximately ovoid in shape. The envelope is made of two parts, the 45 casing 11 and the bladder 12. The casing 11 is made of light parachute or balloon cloth, preferably from fabrics weighing approximately one ounce per square yard. The casing 11 is made up from the circular nose and tail patches 13 and 14 50 which are joined by the lunes 15. Any method of seaming the lunes and patches may be used, but lock-stitch sewing with a thread made from the same material as the casing has proved most satisfactory. The casing 11 contains and is inflated by a very light rubber bladder 12 (in Fig-

ure 3) which may be made from any extensible elastic polymer having rubber-like characteristics, but is highly satisfactory when made from polymerized chloro-butadiene 1,3 because of the low rate of hydrogen diffusion through this substance. The bladder 12 is inflated through the inflation valve 16 (Figures 1 and 2), which is a rubber check-valve of the standard construction adopted for meteorological balloons. The casing 11 carries four cloth fins 17, 18, 19, 20, preferably made in two sections to present a selvage edge both to the leading and to the trailing edge of the fin, which are sewn to the casing along certain of the lune seams 21. These fins form the horizontal lifting surfaces and the vertical stabilizing surfaces and are held extended by light struts 22, of wood or light metal tubing, which are anchored at their outer ends in small tape pockets 23 sewn on the tips of the fins and have their inner ends held on the envelope by cloth sockets 24 sewn on the lune seams. To prevent an air pocket forming, the struts 22 which support the lifting-fins 17 and 19 should be located on the under side of the fin, as shown in Figure 3. Cloth rigging loops 25 are sewn on certain lune seams between the vertical and horizontal fins to provide anchorage for the guys 26—26, which are stretched between the loops 25 and the tips of the fins. Each strut 22 is of a length equal to the radial extension of the adjacent fin, but the guys are so proportioned that the pair of guys supporting one fin are not long enough to permit the end of the strut to move out to the normal periphery of the envelope. Instead, the base of the strut lies at a point well inside the normal periphery and the envelope swells out on each side. The fin, therefore, springs from the envelope along a substantial crease or depression when the envelope is fully expanded. If, for example, the diameter of the balloon is 39" when fully inflated, the radial dimension from the central axis to the base of any strut is preferably about 17 inches.

This kite balloon flies on the lifting-fins 17 and 19 and is held on course by vertical stabilizing-fins 18 and 20. It is quite necessary that the lifting-fins 17 and 19 be symmetrical, but it is not necessary, although it is convenient, to make the stabilizing-fins the same size as the lifting-fins. Furthermore, it is not necessary that stabilizing-fin 18 be the same size as stabilizing-fin 20, the requirement being merely that sufficient vertical fin expanse be given to prevent yawing and to hold the nose of the balloon into the wind.

The balloon is attached to the antenna or to the flying line by means of a harness 27 which is made up of six cords extending from small loop patches 28 sewn on the lune seams 21 to a concentration ring 29 located beneath the balloon. The longest pair of cords stretches from the concentration ring to symmetrically spaced loops located beneath the fins near the stern of the balloon. The second pair stretches between the ring and loops located forward of the fin struts and adjacent the maximum diameter of the envelope. A third and the shortest pair of cords stretches from loops adjacent the nose to the concentration ring. The antenna or the flying cord snaffle 30 is attached to the concentration ring.

In designs of the balloons where collapsibility (to pack in a small "ditching kit") is not important, the fins can be made of rigid members instead of being made of sheets of cloth. In this case, the fin is its own strut and the separate struts 22 are unnecessary.

The operation of the balloon is as follows.

After hydrogen has been admitted through the valve 16 by inserting the nozzle of the sea-generator into the valve and the balloon has been inflated to assume the cross-section shape shown in Figure 3, the externally directed pressure of the hydrogen puts the balloon envelope under tension and pushes the struts out radially, thus maintaining the fins straight, stiff, and in flight condition. The hydrogen diffuses through the envelope slowly during flight. Until the hydrogen has diffused to such a degree that the guys 26 become slack and consequently the gas can exert no effective outward thrust upon the struts, the fins remain taut. The balloon will be lifted by the wind until the fins go slack; consequently, once the rate of diffusion of hydrogen through the bladder is known, the time during which the balloon is capable of wind-borne flight may be preadjusted by the length of the guys. This determines the amount by which the struts are pushed inward radially in the initial inflation.

The valuable feature of the invention is that only the lightest of struts and guys are necessary to hold the fins extended (the struts and guys have a total weight of no more than 80 grams); the gas itself is made to hold the fins out stiff and extended for a very long time.

When the hydrogen has diffused to a point where the guys slacken and the fins are no longer stiff, the balloon may be hauled down. If more hydrogen is available, the original flight characteristics of the balloon are completely restored by an additional hydrogen charge; but if, as is more usual, no hydrogen is available, the balloon may be inflated with air. Obviously, inflation with air does not change the residual static lift due to the hydrogen, but it will restore the dynamic lift because the fins will then be held in taut condition again. Since these balloons will fly as very effective kites in winds of two or three miles an hour and upwards, and since winds of this force are almost always encountered at sea, the effective life of the antenna support is extended well beyond the life of the hydrogen charge.

The balloons are stable in flight, maintain the antenna at a high angle to the horizontal independent of wind velocities from 2 or 3 miles an hour to storm violence and have much greater free lifts than other kite-balloons of the same capacity, which must depend on heavier structure to support the lifting and stabilizing surfaces. These advantages are in addition to their long service life, for a volume of hydrogen represented by the volume of the depressions in the envelope must diffuse through the envelope before the flight of the balloons is affected, and diffusion of this large quantity is a matter of many hours.

I claim:

1. An inflated kite balloon having a flexible envelope, on which rest radially outwardly extending lifting-fins the outer ends of which are positioned by flexible guys of such length that some portion of the radial extent of the fin lies inside the normal circumference of the inflated balloon envelope so that the fin rests in a depression when the envelope is fully inflated and loss of inflation will not cause the guys to slacken.
2. An inflated kite balloon having a flexible envelope, on which rest radially outwardly extending lifting-fins the outer ends of which are positioned by flexible guys of such length that some portion of the radial extent of the fin lies inside the normal circumference of the inflated

balloon envelope so that the fin rests in a depression when the envelope is fully inflated, the gas pressure within said balloon acting to push the fins outwardly and to hold the guys tight until the gas pressure drops below a predetermined point.

3. An inflated kite balloon having a flexible envelope provided with radially outwardly extending flexible fins for lifting and stabilizing the balloon in captive flight supported by struts the outer ends of which are positioned by flexible guys of such length that some portion of the radial extent of the strut lies inside the normal circumference of the inflated balloon envelope so that the fin springs from a depression when the envelope is fully inflated and loss of inflation will not cause the guys to slacken. 15

4. An inflated kite balloon having a flexible envelope provided with radially outwardly extending flexible fins for lifting and stabilizing the balloon in captive flight, struts holding the fins extended which are positioned by flexible guys, some portion of the radial extent of the strut lying inside the normal circumference of the inflated envelope so that the fin springs from a depression when the envelope is fully inflated, the gas pressure within said balloon acting to push the struts outwardly and to hold the guys taut until the gas pressure drops below a predetermined point. 10
